2 Sheets-Sheet 2

UNITED STATES PATENT OFFICE.

HARRY A. CUMFER, OF CHICAGO, ILLINOIS, ASSIGNOR TO GUYTON & CUMFER MFG. CO., A CORPORATION OF ILLINOIS.

LOOPER.

Application filed March 21, 1921. Serial No. 454,248.

To all whom it may concern:

Be it known that I, HARRY A. CUMFER, a citizen of the United States, residing at Chicago, in the county of Cook and State of Illinois, have invented certain new and useful Improvements in Loopers, of which the following is a specification.

The invention relates to improvements in loopers or take-ups used in the manufacture of sheet roofing.

One of the objects of the invention is to provide a new device of this character.

In the manufacture of sheet roofing, continuous sheets of felt, or similar material forming the base for sheet roofing are saturated with a water proofing material, such as asphaltum, or the like, and put through other processes and machines in the act of making the finished product. The sheet is necessarily kept in constant uniform motion in its path through the baths of the asphaltum and during the application thereto of a plastic substance and while the slate covering is being applied. Between these various steps, necessary for the conversion of the felt sheet into rolls of roofing, segregated shingles or shingle-simulating strips, the sheet, with its saturant and subsequently with its plastic coating, is heated to very high temperatures and it becomes highly desirable for the sheet to become relatively cool before entering upon the following steps of its treatment in the progress of completion. It is inexpedient to stop the operation of the apparatus or machines necessary in its manufacture to give it time to cool to the desired degree, and to stretch it out in a single longitudinal sheet between the machines operating thereon would entail housing space too large and expensive to be seriously considered. Furthermore, as the sheets of felt come in large rolls, the sheets of the rolls must be joined together to constitute, in effect, a continuous sheet as it passes through the various baths and machines required for its conversion into the desired product, otherwise the very undesirable task of threading a new sheet through the various machines and hot baths becomes necessary. This is a disagreeable and expensive operation and must be avoided in conducting an efficient mode of procedure in the process of manufacture.

To permit the parts of the sheet being operated on to stop in its movement to point

of completion would produce an ununiform product and disorganize the harmonious co-operation of the various machines and processes and disturb their timed relation.

The invention, which is subject of this application, in a practical embodiment, consists of an elongated frame having a series of constantly moving, spaced-apart supports from which are suspended, in the aggregate, an extended length of the hot sheet, formed thereon into a series of vertical traveling loops, so arranged that the loops taken from the far end of the machine and those put on at the near end of the machine do not have any modifying effect on the movement of the sheet before or after it is arranged on the looper and, therefore, the movement of the sheet at one end of the looper may be stopped, for a limited period of time, necessary to join it to the sheet of another roll without disturbing the movement of the sheet as it leaves the looper or thereafter.

In the drawings:

Fig. 1 is a side elevation of an embodiment of the invention.

Fig. 2 is an end elevation of the looper.

Fig. 3 is an enlarged sectional view of a fragment of the machine showing the means for forming the loops of uniform length, in one position.

Fig. 4 is a similar view showing position of the parts while the loop is being formed.

Fig. 5 is a sectional view of gear mechanism for driving the looper alternatively at normal speed, and at higher speed to replenish the loops thereon after the finishing end of a sheet has been stopped in its progress for connecting it to the begining end of another roll.

In all of the views the same reference characters are used to indicate similar parts.

In the structure shown in the drawings embodying the invention, a series of spaced-apart posts 11-12 and 13, preferably of angle iron, are joined at the top and bottom by cross bars 14, 15 and 16 to opposite posts such as 13'. The posts are also connected together on the respective sides by the longitudinally extending bars 17 and 17'.

Trackways are provided for the loop supports by the angle irons 18 and 18' at the top and similar bars 19 and 19' at the bottom which are parallel and are connected to the upright posts.

22 A pair of brackets 20 are secured to the posts 11, near their respective top ends to support a transverse shaft 21. Secured to the shaft 21 are a pair of sprocket wheels 22 in vertical planes with the track bars 18 and 18', respectively. At the lower ends of the posts 11 brackets 23 are secured to support a transverse shaft 24 to which are secured a pair of sprocket wheels 25 in the vertical planes of the tracks 19-19', respectively. The brackets 23 are each provided with a slideable shaft bearing 26 which is movable along the guides 27, provided on the brackets, by a screw 28 for the purpose to take up slack in the chains 29-29' which move along the tracks 18-18' and 19-19', respectively, and which pass around the pair of sprocket wheels 22 and 25, respectively. Another pair of brackets 30-30' are fixed to the posts 13-13', respectively, near their top ends to support a transverse shaft 31 to which are secured the sprocket wheels 32-32' for driving the chains 29-29'.

25 The chains are connected together at frequent uniform intervals by transversely extending bars 33. These bars have their ends resting on the horizontal tracks 18-18' and 19-19'. Another pair of sprocket wheels 34-34' are connected to a transverse shaft 35 that finds bearings 36-36' that are carried by the posts 13-13'.

Parallel with the frame is a power shaft 37 finding bearings in floor standards 38. 36 A sleeve 39 passes thru the bearing of the standard 38 and over the shaft 37 bears on one end a clutch member 40, and on the other end a miter gear 41. A slideable clutch member 42 is made rotatable with the shaft 37 by the feather 43. The clutch member is moved into driving contact with the member 40 by the lever 44 which is pivoted thereto and to the floor, as at 50. When the clutch members are in contact the miter gear 41 is rotated.

Another, similar, miter gear 45 is loose on the shaft 37 and bears a clutch member 46. A slideable clutch member 47 is made rotatable with the shaft 37 by the feather 48. It 50 is slidably moved on the shaft by a lever 49 pivoted thereto and to the floor, as at 50'. The levers 44 and 49 are connected together by a bar 51 so that when the levers are moved to the left gear wheel 45 will be rotated and gear wheel 41 will be loose on the shaft 37. If the levers be moved in opposite direction the wheel 41 will be driven by the shaft and gear wheel 45 will be loose thereon.

60 A vertical shaft 52 finds a step bearing in the hub 53 on the standard 38. It also has bearing supports in the brackets 54-55 and 56, that are secured to the post 13. Near the lower end of the shaft 52 is fixed a double miter gear wheel 57-58 in mesh with the gear wheels 41 and 45, respectively.

When the gear 41 is driven by the shaft 37 the upright shaft 52 will be driven at a relatively high speed and when the wheel 45 is rotated by the shaft 37, the shaft 52 will be driven at normal and relatively slower speed.

Connected to the top end of the upright shaft 52 a miter gear 59 is in mesh with a similar gear 60 which is fixed on the end of a transversely extending shaft 61 which finds bearings in the blocks 62 and 63, that are fixed to the posts 13-13'. The shaft 61 carries a feed roller 64. Another transversely extending shaft 65 is supported in bearings 66 and 67.

The shafts 61 and 65 are geared together by gear wheels 68 and 69, so that the rollers 64 and 70, the latter being mounted on the shaft 65 will be rotated to feed the sheet 71 into the looper.

Extending from the brackets 62 and 63 are outwardly extending arms 72 and 73, in which a frame 74 is pivotally supported, as at 75, and in the free ends thereof are bearings 66 and 67 for the shaft 65. A lever 76 is connected to the frame, as at 77, which extends beyond the fulcrum point 75 and bears on its inner end a weight 78 which causes the rollers to frictionally engage the sheet 71 sufficiently to feed it. When the weight is raised and the rollers separated, the sheet no longer will be fed.

On the shaft 61 is a sprocket gear 79 which is connected by a sprocket chain 80 to a much larger sprocket wheel 81, that is mounted on a transverse shaft 82 mounted in bearings 83-83', secured to the posts 13-13'. Another sprocket gear 84 is fixed to the shaft 82, connected to the sprocket wheel 85, that is fixed to the shaft 31 by the chain 86. The sprocket wheels 32 and 32' are also fixed to the shaft 31 and by this means the pair of chains 29-29' are driven, its direction of motion at the top is from right to left, looking at Fig. 1.

Pivoted to the posts 13-13' are a pair of rods 87, as at 88. They carry on their free ends an axially adjustable bearing block 89 for a transversely extending shaft 90.

The shaft 90 carries a roller 91, more clearly shown in Figs. 3 and 4. As the chains 29-29' with their connected sheet supports 33 move to the left the roller 91 mounts the approaching support 33 and holds the sheet while a new loop 92 is being formed. About the time the support 33 is moved out from under the roller the new formed loop is about one-third of the length of its fellows and thereafter will continue in its formation until the beginning of the next loop. The speed of the chains without changing the speed of the sheet is the controlling factor determining the lengths of the loops.

Now, assume that it becomes desirable to

splice the sheet 71 without interfering with the movement of the sheet after it leaves the looper. The clutches should be opened to stop the movement of the chains 29—29' and 5 this will also stop the feed of the sheet. The loops will now be removed from the left end of the looper, one at a time. There are enough loops on the machine to permit more than enough time to join the sheet to that of 10 a new roll.

After the joint has been completed clutch members 40—42 are brought into driving contact by movement of hand levers 44 or 49 to the right, whereupon miter gear 41 will 15 be positively driven which will move the chains, sheet supports and sheet feeding rollers at a considerably increased velocity, thereby filling the machine with as many loops as have been taken off during the necessary stop. When the deficiency has been 20 supplied and the machine substantially filled with loops, the handles 44—49 are moved in the opposite direction to close clutch members 46 and 47 and open the clutch members 25 40—42, whereupon miter gear 45 will drive the aforesaid moving instrumentalities at a slower and normal speed.

The looper may be used only as means to cool the sheet, and they may be located at intervals in a system provided for making roofing. After the sheet has been subjected to the effect of the hot asphalt, it would immediately be passed into a looper to cool it in condition to receive the next treatment to 35 which it is to be subjected. In a looper used for this purpose the loops will be moved continuously at all times without interruption, as above described.

The normal movement of the sheet thru 40 the looper should be at substantially the same and uniform speed at which it is moved while undergoing other treatments necessary before the product is completed.

Having described my invention what I 45 claim as new and desire to secure by Letters Patent, is:—

1. A device for arranging a continuous sheet of constantly moving fabric in uniform, parallel loops, comprising a frame; 50 transversely positioned, uniformly spaced-apart, parallel supports, one for each loop; means for bodily and continuously moving said supports along a common path on said frame; means to hold the fabric on each 55 support consecutively while moving, whereby to form a loop between adjacent supports and means to accelerate formation of subsequently formed loops.

2. A device for arranging a continuous 60 sheet of constantly moving fabric in uniform, parallel loops, comprising a frame; transversely positioned, uniformly spaced-apart, parallel supports, one for each loop; means for engaging opposite ends of said 65 support to bodily, uniformly and consecu-

tively move them along a common path on said frame; means to move the fabric into engagement with said supports; means to hold the fabric on each support, consecutively, while moving therewith whereby to 70 form loops between adjacent supports and means to accelerate loop formation.

3. A device for arranging a continuous sheet of constantly moving fabric in uniform, parallel loops, comprising a frame; 75 parallel, spaced-apart, horizontal tracks on said frame; a pair of chains movable along said track; transversely extending spaced-apart supports having their ends resting on the respective tracks and connected at intervals to the adjacent chains; means to feed a fabric to be looped to said moving supports; means to hold the fabric on a support adjacent the feeding means to form loops between adjacent supports and means 80 to change the speed of the moving fabric.

4. A device for arranging a continuous sheet of constantly moving fabric in uniform, parallel loops, comprising a frame; 85 transversely positioned, uniformly spaced-apart, parallel supports arranged in a horizontal plane, one for each loop; means for bodily and continuously moving said supports at a given speed along a common path, on said frame, means to hold the fabric on each support, consecutively while moving whereby to 90 form a loop between adjacent supports; and means to change the speed of the loop forming operation to compensate for those that may be removed from the frame.

5. A device for arranging a continuous sheet of constantly moving fabric in uniform, parallel loops, comprising a frame; 95 transversely positioned, uniformly spaced-apart, parallel supports, one for each loop; means for bodily and continuously moving said supports along a common path on said frame; means to hold the fabric on the last moving support while the next loop is being formed; means for stopping the movement of the fabric and means to accelerate the speed of the fabric to compensate for the time the fabric is not moving.

6. A device for arranging a continuous sheet of constantly moving fabric in uniform, parallel loops, comprising a frame; 115 transversely positioned, uniformly spaced-apart, parallel supports, one for each loop; means for bodily and continuously moving said supports along a common path on said frame; means to hold the fabric on the last moving support while a part of the next loop is being formed; means to feed the sheet to the supports; means to stop the movement of the sheet into the looper and to stop the movement of the loops and means to accelerate movement of the sheet.

In testimony whereof I hereunto subscribe my name.

HARRY A. CUMFER.
